[57] CLAIM

The ornamental design for an eye shadow compact, as shown and described.

DESCRIPTION

FIG. 1 is a perspective view of an eye shadow compact showing our new design in open condition;

FIG. 2 is a top plan view thereof in closed condition;

FIG. 3 is a bottom plan view thereof;

FIG. 4 is a front elevational view thereof; and

FIG. 5 is a cross sectional view taken on line V—V of FIG. 3.
